(57) **CLAIM**

The ornamental design for a LED thermal therapy device, as shown and described.

DESCRIPTION

FIG. 1 is a front perspective view of a LED thermal therapy device, showing my new design in an assembled configuration with a device engaged with a charging station;

FIG. 2 is an exploded front perspective view thereof, illustrated with the device exploded away from the charging station;

FIG. 3 is an exploded front elevational view of FIG. 2;

FIG. 4 is an exploded rear elevational view of FIG. 2;

FIG. 5 is an exploded left-side elevational view of FIG. 2;

FIG. 6 is an exploded right-side elevational view of FIG. 2;

FIG. 7 is an exploded top plan view of FIG. 2; and,

FIG. 8 is an exploded bottom plan view of FIG. 2.

The broken lines in the figures depict portions of the LED thermal therapy device that form no part of the claimed design.

1 Claim, 7 Drawing Sheets
